UNITED STATES PATENT OFFICE.

LEO SCHILDKNECHT, OF ST. LOUIS, MISSOURI, ASSIGNOR TO LANDIS MACHINE COMPANY, OF ST. LOUIS, MISSOURI, A CORPORATION OF MISSOURI.

THREAD-CASE TENSION.

Application filed February 4, 1922. Serial No. 534,215.

To all whom it may concern:

Be it known that I, LEO SCHILDKNECHT, a citizen of the United States, residing at St. Louis, Missouri, have invented a certain new and useful Improvement in Thread-Case Tensions, of which the following is a full, clear, and exact description, such as will enable others skilled in the art to which it appertains to make and use the same, reference being had to the accompanying drawings, forming part of this application.

My invention relates to thread cases such as are used in shoe sewing machines for containing a thread bobbin and consists in an improved thread tension device for such cases.

The object of my invention is to provide an efficient adjustable tension device low in cost and easily adjusted.

In the accompanying drawings which illustrate a preferred form of my invention,—

Figure 1 is a top view of a thread case to which my invention is applied.

Figure 2 is an edge view of the thread case showing my tension device.

Figure 3 is another edge view of the case taken at right angles to Figure 2.

Figure 4 is a section on line 4—4 of Figure 2.

The thread case 1 is shaped like a shallow cup and is of a form in common use and needs no particular description as to its construction or operation. It is provided with a peripheral groove 2 extending part of the way around the case and having a depth approximating a half of the thickness of the case wall. An integral finger 3 extends upwardly and outwardly from the case. A thread opening 4 extends from groove 2 through finger 3 and spaced a short distance from opening 4 is a second thread opening 4^a connecting the interior of the case with groove 2.

Positioned in groove 2 is an arcuate thread engaging member 5, preferably made of spring steel, and fixedly secured by rivets or otherwise at one end 6 to the wall of the case. Near the unfixed end of member 5 the member is bent downwardly and upwardly as at 7 to permit unobstructed passage of a thread through the case wall and to engage the thread as at 8 and to press same against the upper edge of groove 2.

To control the pressure of member 5 on

the thread, I provide a cam 9, pivotally mounted in a recess 10, which is located in the edge of the case and intersects groove 2. Cam 9 is preferably polygonal throughout the larger portion of its perimeter, the successive sides being spaced at increasing distances from the center of the cam. One portion of the cam's periphery is provided with extending tongues 11 spaced from each other to permit the insertion of a knife blade or other tool to turn the cam on its pivot to bring various edges of the cam in contact with member 5. It is obvious that by means of the cam the space between the upper edge of member 5 and the top edge of groove 2 may be varied to accommodate different sizes of threads and different tensions required. Due to the polygonal construction of the cam, any adjustment made will be positively retained so that no additional means are required for holding the cam in any adjusted position.

As previously mentioned member 5 is preferably of spring material and is "set" so that it tends to press against cam 9; consequently there will always be the maximum opening at 8, which the cam will permit. The eccentric is spaced a substantial distance from the unfixed end of member 5 so as to permit a yielding engagement of the thread by this end of the tension member.

The above described tension device is comparatively easy and economical to manufacture, is readily adjustable, and positive in its action. The invention embodied is capable of being applied in various forms and I contemplate all such modifications as fall within the scope of the following claims.

I claim:

1. In combination, a circular thread case having a peripheral groove with a thread engaging surface, a friction member in said groove having a thread engaging surface at one end opposed to said groove surface, a pivot fixed on said case, and a cam journaled on said pivot and engaging said member at a point between its ends spaced substantially from its thread engaging surface.

2. In combination, a circular thread case having a peripheral groove with a thread engaging surface, a friction member in said groove having a thread engaging surface opposing said case surface, and a polygonal

- cam pivoted at a fixed point on the side of said case having straight faces for engaging said movable bearing element located at different distances from its pivot whereby 5 rotation of said cam adjusts said movable bearing element relative to said fixed bearing element.
3. In a circular thread case having a peripheral groove and thread openings leading to and from said groove, a member in said groove adapted to oppose one edge of the groove to frictionally engage a thread passed through said openings, and a cam sunk in the periphery of said case and movable on an axis extending radially of the case with its edge having adjusting contact 10 with said member.
4. In a circular thread case having a peripheral groove, an arcuate thread engaging member located in said groove and having one end fixed to said case and its other end movable across said groove to adjust the space between one side of the member and the side of the groove, a recess in the periphery of said case adjacent said groove, a polygonal cam pivoted in said recess on an axis extending radially of the cam and projecting into said groove and engaging the opposite side of said member 15 near its movable end. 20 25 30

In testimony whereof I hereunto affix my signature this 31st day of January, 1922.

LEO SCHILDKNECHT.
